UNITED STATES PATENT OFFICE.

VICTOR ULMER, OF ROSHEIM, GERMANY, ASSIGNOR TO MASCHINENFABRIK AUGSBURG-NÜRNBERG A. G., OF NUREMBERG, GERMANY.

COOLING MEANS FOR INTERNAL-COMBUSTION ENGINES.

1,123,431.

Specification of Letters Patent.

Patented Jan. 5, 1915.

Application filed June 23, 1914. Serial No. 846,725.

To all whom it may concern:

Be it known that I, VICTOR ULMER, subject of the German Emperor, and residing at Rosheim, Alsace-Lorraine, Germany, have invented certain new and useful Improvements in Cooling Means for Internal-Combustion Engines, of which the following is a specification.

My invention relates to internal combustion engines and more particularly to means for cooling the working pistons of such engines. As a rule, the cooling medium—water, oil, or the like—is conveyed to the piston through so-called telescopic tubes, which participate in the reciprocating movement of the piston. However, unless the axis of the piston and of the telescopic tube are exactly parallel, a leakage will soon occur permitting the cooling medium to escape around the telescopic tube, where the latter passes through the stuffing box. This is caused by the lateral pressures in the guides of the telescopic tube, whereby the packing of the stuffing box becomes gradually loosened and it finally is so damaged, that it not only allows the cooling medium to escape, but may result in a serious breakdown of the entire engine.

To avoid these defects, is the object of my present invention, according to which I interpose between the telescopic tube proper and the supply-pipe attached to the piston an elastic member, to compensate for irregularities in the reciprocating movements of

the piston and the telescopic tube.

In the accompanying drawing I have illustrated one form of construction showing how my invention can be applied to the piston of a single-acting internal combustion engine, the drawing being a central longitudinal section through the cylinder and piston and one of the telescopic tubes.

a is the piston adapted to reciprocate in the cylinder *c* and provided at its inner end with a closed part *b*, which is cooled by a continuous flow of a cooling medium, *e. g.* oil, which enters part *b* at *d* and leaves it at *e*. For the purpose of conveying the oil to and conducting it away from *b*, the walls of the piston *a* are cast with ducts *f* which, in turn, communicate with pipes *g* attached to the outer or forward end of the piston.

To the walls of the cylinder *c* on opposite sides thereof, are secured brackets *h*. One of these brackets is intended as a guide

for the oil-supply-pipe and the other for the oil discharge pipe, the former being shown in the drawing in section. Both being of like construction, the description of one will suffice.

l is the telescopic tube proper, which reciprocates as the piston *a* reciprocates and is guided in the bracket *h*, a stuffing-box *n* being provided to prevent leakage. Any oil escaping around tube *l* between this tube and the inner wall of the bracket *h* is discharged at *m*. To the bracket is secured a cylindrical cover *i*, surrounding the tube *l* and provided with an inlet opening *k* through which the oil enters filling the space inside the cover *i*.

Instead of connecting the telescopic tube *l* directly with pipe *g*, I interpose a tube *o*, which, with its one end, is secured to the inner end of the telescopic tube *l* so that the oil instead of flowing through the latter, passes through tube *o*. This tube, on account of its being secured to the inner end of tube *l* only with its free end, is thereby made more or less elastic, which elasticity, of course, will compensate for any small irregularities in the movements of the reciprocating piston *a* and the pipe *g* attached thereto, on the one hand, and of the likewise reciprocating telescopic tube *l*, on the other hand. Thus, the stuffing-box *n* will be relieved of all strain, or lateral pressure, and will, therefore, hold tight for a long time.

My new construction can, of course, be used, with any cooling medium and can be equally well applied to vertical and horizontal engines.

I claim as my invention:

1. In internal combustion engines the combination with the cylinder and the reciprocating piston provided with passages for the circulation of a cooling medium, of a telescopic tube adapted to reciprocate together with the said piston and to supply the cooling medium thereto, a communicating connection between said telescopic tube and one of the passages in said piston and an elastic member in said connection, and means for guiding said telescopic tube.

2. In internal combustion engines the combination with the cylinder and the reciprocating piston provided with passages for the circulation of a cooling medium, of a telescopic tube adapted to reciprocate to

gether with the said piston and to supply the cooling medium thereto, a communicating connection between said telescopic tube and one of the passages in said piston, and 5 a tube in said telescopic tube forming part of said connection and being secured with its free end to the inner end of said telescopic tube, and means for guiding said telescopic tube.

10 3. In internal combustion engines the combination with the cylinder and the reciprocating piston provided with passages for the circulation of a cooling medium, of two guiding brackets, a telescopic tube adapted 15 to reciprocate in each bracket together with

the piston, a communicating connection between each tube and a passage in said piston to conduct the cooling medium to and away from the piston respectively, and an elastic tube in each telescopic tube secured 20 with its free end to the inner end of the telescopic tube and forming part of the connection between said telescopic tube and the piston.

In testimony whereof I affix my signature 25 in presence of two witnesses.

VICTOR ULMER.
